UNITED STATES PATENT OFFICE.

CHARLES STANLEY ROGERS, OF PHILADELPHIA, PENNSYLVANIA, ASSIGNOR TO THE PROCESS ENGINEERING COMPANY, OF PHILADELPHIA, PENNSYLVANIA, A CORPORATION OF PENNSYLVANIA.

PUMP.

1,159,868.

Specification of Letters Patent.

Patented Nov. 9, 1915.

Application filed December 9, 1913. Serial No. 805,585.

To all whom it may concern:

Be it known that I, CHARLES STANLEY ROGERS, a citizen of the United States, residing in Philadelphia, Pennsylvania, have 5 invented certain Improvements in Pumps, of which the following is a specification.

My invention consists of a pump designed especially for pumping acid or other corrosive liquid, although not restricted to 10 such special use, the object of my invention being to so construct such a pump as to permit removal or replacing of the impeller without the necessity of first draining the pump. This object I attain in the manner 15 hereinafter set forth, reference being had to the accompanying drawings, in which—

Figure 1 is a view, partly in side elevation and partly in vertical section, of pumping apparatus constructed in accordance 20 with my invention; Fig. 2 is an enlarged vertical sectional view of part of the apparatus; Fig. 3 is a horizontal section on the line *a—a*, Fig. 2, and Fig. 4 is a view similar to part of Fig. 1 but illustrating my invention 25 as applied to a modified form of pump.

In Figs. 1, 2 and 3 of the drawing, I have illustrated my invention as applied to a rotary pump driven by an electric motor, 1 representing the cylindrical casing of the 30 pump, 2 the bottom of the same rigidly secured to or forming part of said cylindrical casing, 3 the rotary impeller, and 4 the top of the casing which is detachably secured to the cylindrical member 1 in the manner 35 hereinafter set forth.

The bottom 2 of the casing has, in the present instance, a central opening closed by a plug 5 which constitutes a step bearing for a stud 6 depending from the center of the 40 impeller 3 from which projects upwardly a shaft 7, whereby said impeller is rotated, the upper end of said shaft being connected by a coupling 8 to a short shaft 9 which is adapted to a thrust bearing 10 and is connected 45 by a flexible coupling 11 to the armature shaft 12 of an electric motor 13, which constitutes the motive power for the pump and is mounted upon a supporting structure 14 of any suitable character. The term "flexible coupling" as here used is intended to mean one which will transmit power from the shaft 12 to the shaft 9 even although 50 said shafts are not in alinement with one another.

The top plate 4 of the pump casing has a 55 central opening 15 for the inflow of the liquid which is to be pumped, and mounted upon the casing 1 of the pump is a cylindrical reservoir 16 exceeding in diameter the diameter of the top plate 4 of the pump, this 60 reservoir 16 communicating through a valved pipe 17 with a feed tank 18 and also having, at its upper end, an overflow pipe 19 discharging into said tank 18.

The casing 1 of the pump has an annular 65 chamber 20 communicating with the central chamber in which the impeller rotates, and said impeller is so constructed as to receive the incoming supply of liquid at the center of the pump and discharge the same into the 70 annular chamber 20, from which it escapes through the discharge pipe 21. Any suitable form of rotary pump may, however, be employed, so long as the top plate of the 75 same is readily removable and the impeller can be withdrawn from the pump when said top plate is removed. In the present instance, the top plate of the pump is held in place upon the annular casing 1 by means of screws 22 passing through nuts 23 which 80 are secured to or form part of plates each engaging at each end a hooked lug 25 on the top of the cylindrical casing 1 of the pump, such lugs being disposed within the cylinder 16 but outwardly beyond the periphery of 85 the top 4 of the pump. The nuts 23, however, overlap the top plate of the pump so that when the screws 22 are properly manipulated they will press downwardly upon 90 said top plate and seat it firmly in its bearing on the cylindrical casing 1 and at the same time will exert upward pressure on the nuts 23 so as to engage the ends of their plates firmly with the hooked lugs 25.

Normally, the level of liquid in the reservoir 16 may be at the overflow pipe 19, the liquid flowing from the tank 18 through the pipe 17 into the reservoir 16 and being withdrawn from the lower portion of the same through the central opening 15 in the top 100 plate 4 of the pump casing. If, for any reason, it becomes necessary to remove the impeller 3 this can be readily effected without necessitating the draining of the pump casing or reservoir 16 by first slackening off the retaining screws 22 and then disengaging their plates from the lugs 25 and removing the screws 22, and nuts 23, from the casing 16,

the screws being provided with long stems 24 in order that these operations may be conducted from a point above the top of the reservoir. The top plate 4 of the pump casing being now unconfined can be readily withdrawn from the reservoir, as for instance, by means of hooked rods engaging openings 26 in said top and the impeller 3 can then be removed by means of its shaft 7.

10 The parts can be readily restored to operative position by reversal of the above described operations.

My invention is not limited in its application to a rotary pump but can be applied 15 as well to a reciprocating pump having an impeller in the form of a piston or plunger. Such a pump is shown in Fig. 4, the parts corresponding to those of the pump shown in Fig. 1 being provided with the same reference numerals, distinguished from those 20 of Fig. 1 by the addition of the letter "a."

When the pump is intended for pumping

acid or other corrosive liquid the parts which come in contact therewith should be composed of or coated with material which 25 will resist corrosion.

I claim:

The combination of a pump casing having a liquid reservoir extending above the same, a detachable top plate for said pump 30 casing removable through said reservoir, clamp screws for said top plate distributed around the periphery of the same, nuts engaged by said clamp screws, and nut retaining devices distributed around the top 35 plate and open on one side to permit ready insertion or removal of the nuts.

In testimony whereof, I have signed my name to this specification, in the presence of two subscribing witnesses.

CHARLES STANLEY ROGERS.
